(57) **CLAIM**

What is claimed is the ornamental design for a tool belt, as shown and described.

DESCRIPTION

FIG. 1 is a perspective view of a tool belt being worn by a person, with the dashed lines showing the outline of a person wearing the tool belt for illustrative purposes only and forming no part of the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view of an alternate embodiment of the tool belt of the present invention; and,

FIG. 9 is a perspective view of the embodiment of the tool belt of the present invention shown in FIG. 8 being worn by a person, with the dashed lines showing the outline of a person wearing the tool belt for illustrative purposes only and forming no part of the claimed design.
